NONMICROPHONIC SOCKET

Louis R. Wanner, Philadelphia, Pa., assignor to
 Hugh H. Eby, Inc., a corporation of Pennsylvania

Application November 26, 1945, Serial No. 630,845

4 Claims. (Cl. 173—328)

1

My invention relates to a socket for the reception of an electronic tube, and relates particularly to a non-microphonic miniature socket.

Heretofore, it has been customary to manufacture electronic tube receiving bases or sockets that are adapted to be mounted directly upon a chassis by suitable means such as rivets, bolts and nuts, or eyelets, which chassis may be made of metal, or a synthetic resin. However, these prior art devices enable sound or shock to be transmitted from the chassis through the socket to the tube which sets up vibratory motion of the tube elements and hence causes the tube to be microphonic.

It is, therefore, an object of my invention to provide a socket or tube base for an electronic receiver or transmitter whereby mechanical vibration will be reduced to a minimum value.

It is another object of my invention to provide a base for an electronic tube device whereby physical vibrations from a loud speaker, or sound translator, or other mechanical vibrations will not be transmitted through the socket to the tube.

Another object of my invention is to provide an electronic tube socket which is physically cushioned from the chassis.

Another object of my invention is to provide an electronic tube socket which may be mounted either above or below a chassis and remain cushioned from the chassis.

Another object of my invention is to provide an electronic tube socket which may be mounted either above or below the surface of a chassis simply by changing the location of some of the elements of the socket.

Another object of my invention is to provide an electronic tube socket resiliently cushioned along a line support from the chassis.

Other objects of my invention are to provide an improved device of the character described, that is easily and economically produced, which is sturdy in construction, and which is highly efficient in operation.

With the above and related objects in view, my invention is typified by the details of construction and combination of parts, as will be more fully understood from the following description, when read in conjunction with the accompanying drawings in which:

Fig. 1 is a plan view of an electronic tube socket embodying my invention.

Fig. 2 is a fragmentary side elevational view looking from the line 2—2 of Fig. 1 showing the socket mounted above the surface of the chassis.

2

Fig. 3 is a view taken along the line 3—3 of Fig. 1.

Fig. 4 is a bottom view of the socket embodied in my invention mounted upon a chassis.

5 Fig. 5 is a fragmentary side elevational view of the socket embodying my invention when the socket is positioned below the surface of the chassis.

10 Fig. 6 is an exploded view of the two resilient washers or rings, one of which is a locating washer or ring.

Fig. 7 is a fragmentary plan view showing the position of the resilient locating ring together with the socket.

15 Fig. 8 is an enlarged fragmentary view showing the spacing of the cushioning washers from the socket housing whereby free floating action of the socket with respect to the chassis occurs.

Referring now in detail to the drawings of my 20 invention wherein similar reference characters refer to similar parts, I show an electronic tube socket which is adapted to be mounted above (Figs. 2 and 3) or below (Fig. 5) and to be completely cushioned from the chassis without any mechanical changes being made in any of the 25 parts and wherein only the location of some of the elements is changed.

A chassis 10 made of any suitable material with suitable socket openings and slots therein for the 30 reception of bendable tabs 12 which slots extend radially from the opening for the tube socket itself. The tabs 12, integrally formed with a metallic holding shell or casing 14, are for the purpose of holding the socket in position upon the chassis 10.

35 The electronic socket comprises a molded insulation, or a phenolic condensation base, generally designated as A, which has suitable metallic terminals, generally designated as B, extending from one end. The quantity, arrangement, and the construction of the terminals B is not the subject of this invention and is further described in my prior filed patent application Serial No. 589,286 now abandoned. Each of a plurality of 40 openings 16 within the base A receive one end of each of the terminals B, and the end of each of the terminals B within the openings 16 is adapted to receive a pin which is upon the end of the electronic tube, the pins and their complementary terminals for the purpose of completing 45 an electrical connection from the electrical terminal to a tube element.

50 The tube base A is substantially cylindrical and it has a horizontally extending central ridge 18 on the outer curved periphery thereof.

The ridge 18 has diametrically opposite cutouts 20 and 22 therethrough which are for the purpose of receiving locating key extensions 24 and 26 integrally formed with the ring 23 of a resilient washer or ring, generally designated as C. The resilient washer C is positioned on the upper edge 18a of the ridge 18 (Fig. 2) and a second resilient washer or ring, generally designated as D, is positioned between the ridge 18 and the top of the chassis 10. Each of the washers C and D, which may be made of rubber, soft fiber, felt, paper, or any natural or synthetic soft material, normally is of a radial thickness which is less than the distance between curved wall 19 of the base A and the inner curved wall 14a of the casing 14; and the radial thickness of the washers is approximately twice the radial width of the ridge 18 from the wall 19 of the base A.

The transverse thickness of the washers C and D normally is less than the distance between the flat surface of the ridge 18 and the surface of the chassis or the flat surface 14b of the casing 14. Hence, when the washers C and D are mounted in position about the base A within the casing 14 and chassis, and the socket is mounted upon the upper surface of a chassis 10, Fig. 2, the lower edge of the ridge 18 of the base A will rest upon the washer D while the washer C will be freely floating away from the casing and the washer C will rest upon the upper surface 18a of the ridge 18. The edge 14c, defining the large opening through the casing 14 for the base A, is located to approximately meet the center of the washer C so that the washer C may be nearly in shearing action between the casing 14 and the ridge 18 of the base A. Hence, substantially a line contact is made between the socket base A and its cushion washer C.

It is to be observed that each of the key extensions 24 and 26 on the ring 23 of the washer C extends equally on each transverse side of the ring, i. e., the extensions 24 and 26 serve the purpose of preventing the rotation of the washer C with respect to the base A, see Figs. 2 and 3.

The metallic casing 14 has suitable key openings 14d and 14e therein to permit the key extensions 24 and 26 of the washer C to interfere therewith so that no relative turning motion may occur between the casing 14 and the washer C, but the two members may be pulled apart transverse of their radial diameter.

A central electrostatic shield, generally designated as F, passes through the base A and extends a sufficient distance away from the lower side of the base to permit a ground wire to be attached thereto.

In order to attach the socket to the underside of the chassis 10, no additional elements are inserted nor are any parts altered, but the position of the washers C and D is exchanged, see Fig. 5, so that the washer D is placed adjacent the chassis. The casing 14, also, is placed beneath the chassis 10 with its holding lugs 12 extending adjacent the upper surface of the chassis.

The washer D, also, is positioned to rest upon the edge 18a of the ridge 18 and away from the edge 21a of the large opening in the chassis 10, so that the washer D is freely floating upon the ridge 18. The base A is freely floating upon the resilient washer C, which is nestled upon the inner surface 14b of the casing 14, hence the socket base A is cushioned from both its casing and the chassis 10.

The extreme peripheral edge 18b of the ridge 18 engages the washer C so that there is a line 75

cushion as compared to a surface contact, and a complete cushioning of the base A from the casing and the chassis occurs. This line cushioning enables the free rocking or floating of the base A with respect to the chassis.

With my invention, unwanted microphonic sounds which ordinarily may occur in the electrical circuit because of the differential gain in the tube where microphonism occurs, are reduced to a minimum value.

The two insulating washers C and D may be made as a single washer or the ridge 18 may be made as a plurality of parts.

Although my invention has been described in considerable detail, such description is intended as being illustrative rather than limiting, since the invention may be variously embodied, and the scope of the invention is to be determined as claimed.

I claim as my invention:

1. A nonmicrophonic electronic tube socket assembly of the character described comprising, in combination, an electronic tube supporting base member having a plurality of circumferentially spaced contact elements respectively adapted to frictionally receive the tube contact pins, said base member being characterized by the provision of a circumferential rib disposed in a plane intermediate the opposite end surfaces 30 of the base member, a mounting for the base member having a circular wall embracing said rib and an inturned annular flange disposed outwardly of the said circumferential rib, said rib and flange being complementally notched to 35 jointly provide a common keyway therebetween, and a pair of resilient, shock-absorbing annular elements embracing the body of said base member and disposed respectively upon opposite sides of said circumferential rib, said elements being 40 each of a radial width approximately equal to the combined radial width of said rib and said inturned flange, one of said elements being provided with oppositely projecting lugs extending parallel to the axis of the socket assembly and 45 adapted for projection respectively into the complemental notches of said keyway to resiliently key said base member and mounting against relative rotation.

2. In a nonmicrophonic socket assembly of the 50 character defined in claim 1 wherein said rib and flange are complementally notched as aforesaid at diametrically opposed points to provide a pair of keyways therebetween; and wherein said last-mentioned shock-absorbing element is provided 55 with a pair of diametrically opposed keying lugs for respective projection into said keyways.

3. In a nonmicrophonic socket assembly of the 60 character defined in claim 1 wherein said circumferential rib and said inturned flange are disposed in parallel planes spaced vertically apart to accommodate therebetween said last-mentioned shock-absorbing element, and wherein said base member is reversible end for end relatively to said mounting to present one side or 65 the other of said circumferential rib in engagement with said last-mentioned shock-absorbing element.

4. In a nonmicrophonic socket assembly of the 70 character defined in claim 1 wherein said mounting for the base is in the form of a sheet metal stamping having at the circumferential edge thereof opposite its said inturned flange a plurality of bendable tabs for securing said assembly upon a supporting chassis with said shock-absorbing elements in respective com-

pression between said chassis and the circumferential rib of the base member and between said rib and the inturned flange of the mounting aforesaid.

LOUIS R. WANNER.
